UNITED STATES PATENT OFFICE.

EDWARD FOOSE, OF WASHINGTON, DISTRICT OF COLUMBIA.

CABINET SYSTEM.

Application filed May 21, 1923. Serial No. 640,585.

This invention relates to certain new and useful improvements in cabinet systems for stores, factories and other places, and like improvements in locker systems for gyms, 5 nasiuns, golf clubs, and other places where private lockers are used.

The object of my invention is to provide an improved arrangement of cabinets or lockers and passageways in a room or other 10 place whereby for a given number of cabinets or lockers of a given size considerably less space is required by using this new arrangement than by placing these cabinets or lockers as is now usually done.

I attain this object by a certain arrangement of cabinets or lockers and passageways in a room or other place whereby the cabinets or lockers and the passageways are placed alternately over each other, and the 15 raised passageways made accessible by stairways, elevators, connecting passageways, or other means.

In the drawings:

Figure 1 is a plan view of the lower part 25 of a room with a certain arrangement of parts;

Figure 2 is a plan view of the lower part of a room with another arrangement of parts;

Figure 3 is a plan view of the upper part 30 of same room and arrangement of parts shown in Figure 1;

Figure 4 is a plan view of the upper part 35 of the same room and arrangement of parts shown in Figure 2;

Figure 5 is a vertical section on line 5—5 of Figure 1;

Figure 6 is a vertical section on line 6—6 of Figure 2;

Figure 7 is a vertical section on line 7—7 40 of Figure 1, enlarged;

Figure 8 is a part of a front elevation on line 8—8 of Figure 7;

Figure 9 is a plan view of upper left part 45 of Figure 3, enlarged;

Figure 10 is a plan view of a part of Figure 4, enlarged;

Figure 11 is a horizontal section through 50 the two end parts on line 11—11 of Figure 7; and

Figure 12 is a vertical section showing another type of construction and installation.

For brevity all structures with one or more compartments, whether cabinets, lockers, or other similar structures will, hereafter, in the description of this specification

be called cabinets; it being understood that it will not limit the application of this invention to this particular class.

In Figures 1, 3 and 5 is shown a preferred 60 embodiment of my invention; Figures 7, 8, 9 and 11 illustrate details of construction and arrangement of this preferred embodiment.

1, 2, 3 and 4 indicate cabinets in rows, 65 made of metal or other fire resisting material and made preferably in unit structures comprising each a plurality of cabinets; where possible such a structure should comprise all cabinets in back to back adjoining rows; 70 as, all cabinets in rows 1 and 2. Passageways 5, 6, and 7 give access to these cabinets 1, 2, 3, and 4; main passageway 8 connects passageways 5, 6 and 7.

Stairway 9 leads to a second main passageway 10 connecting with and affording ingress and egress to passageways 11 and 12; passageway 11 being directly over and supported on cabinets 1 and 2 or parts connected therewith; passageway 12 being directly over and supported similarly on cabinets 3 and 4; main passageway 10 being approximately on the same level as passageways 11 and 12. Space over main passageway is not closed at this level, railing 13 85 being a protecting means from stepping into this open space.

Cabinets 14 are directly over passageway 5, cabinets 15 and 16 over passageway 6, and cabinets 17 over passageway 7; these cabinets should be made of metal or other fire resisting material and, preferably, in unit structures comprising each a plurality of cabinets.

Cabinet bodies 18 have steel angle struts 95 19 connected thereto and secured to steel angle floor support 20 carrying floor boards or slabs 21 of wood, gypsum blocks, reinforced concrete or other suitable material. Steel angle struts 19 extend upward above 100 floor and are secured to one another by steel angle cabinet supports 22. Two of these cabinet supports are secured to each other by braces 23 forming a supporting frame for cabinets 15 and 16. As end row 105 of cabinets 14, are over passageway 5, two steel columns 24 support an I-beam 25 which is connected with cabinet supporting angle 22 by braces 26. These braces 26 are secured to both the I-beam and angle 22.

Cabinet bodies 18 have a front, comprising a base 27, stiles 28 and upper panel 29,

all of sheet metal. A sheet metal ceiling 30 may be used for a neat finish under second row of cabinets 15 and 16. Upper panel 29 may have perforations 31 or other means to permit air circulation.

It is understood that I do not limit the application of my invention to the construction here set forth. One modification of this construction would be desirable if it were contemplated to install the lower cabinet structures and add the upper ones at a later date. This consists in making the lower cabinet structure complete including body 18, angle struts 19, angle floor supports 20 and floor units 21 but not continuing angle struts above the floor 21. When upper cabinet structure would be constructed and installed it would be provided with legs or panels extending from the floor of upper cabinet structure to the floor of passageway 21 and integral with said cabinet structure; or an auxiliary platform could be built and installed spanning lower passageway having legs or panels as described herebefore, and means for securing this platform to the lower cabinet structures, the same being adapted to receive the upper cabinet structure.

In Figures 2, 4, 6 and 10 is shown a modified form of the arrangement illustrated in Figures 1, 3, 5, 7, 8, 9 and 11 and described heretofore. This changed form would be required in a room or other enclosed space where ceiling beams or other obstructions would prevent the main passageway 32 being on the same level as passageways 33; steps 34 having, in this instance, two risers would make up the difference in level, and stairs 35 would have two risers less than stairs 9, assuming all lower cabinets and passageways over them being of the same height and level as shown in Figures 1, 3 and 5.

For this form the lower cabinets, all supporting and connecting members, and floor boards or slabs would be similar to those described heretofore. Upper cabinets 36, 37, 38 and 39 could all be made of any usual or special cabinet construction, making due allowances for beams and other obstructions.

In Figure 12 is shown a form of structure and arrangement which is simple to construct and would be of use in rooms or enclosed places where ceiling height is great enough to permit two or more passageways over each other. Where ceiling is high enough there could be two or more tiers superimposed on the first tier, keeping the arrangement of alternate passageways and cabinets all the way up. This form would be suitable in stores where a large variety of articles is kept and where chutes could be used to convey the articles to certain places.

In this form cabinets 47 are over passage-

way 44, passageway 51 is over cabinets 40 and 41, cabinets 48 and 49 are over passageway 45, passageway 51 is over cabinets 42 and 43, and cabinets 50 are over passageway 46. Floors 52 are substantially on the same level as cabinet supports 53. This could be continued by placing cabinet supports 53 over passageway 51, floor 52 over cabinets 48 and 49, and over these a tier of cabinets over cabinet supports; repeating this arrangement as often at space and structural supports permit.

Having described my invention what I claim as new and desire to secure by Letters Patent, is:—

1. In a cabinet system, the combination of a plurality of lower rows of vertical cabinets arranged back to back and having fronts in spaced relation to define aisles between the rows, and upper rows of vertical cabinets arranged back to back immediately above the lower aisles, the front of the rows of upper cabinets being spaced to define upper aisles immediately above the cabinets of the lower rows.

2. In a cabinet system, the combination of a plurality of lower rows of vertical cabinets arranged back to back and having fronts in spaced relation to define aisles between the rows, and upper rows of vertical cabinets arranged back to back immediately above the lower aisles, the fronts of the rows of upper cabinets being spaced to define upper aisles immediately above the cabinets of the lower rows, certain of the walls of the lower rows of cabinets being extended above the lower cabinets and formed with air conducting means between the upper and lower aisles.

3. The construction set forth in claim 2, supports extending above said rows of lower cabinets, and floors carried by said supports and arranged above said lower rows of vertical cabinets to form the floors of said aisles between the fronts of the upper rows of cabinets.

4. In a cabinet system, a plurality of spaced rows of upper and lower vertical cabinets, the upper rows of cabinets being staggered with respect to the lower rows of cabinets, the spaces between the fronts of the upper rows of cabinets being immediately above the lower rows of cabinets and forming aisles between the upper rows of cabinets.

5. A structure of the class described comprising a plurality of rows of lower vertical cabinets arranged back to back and having fronts in spaced relation to define lower aisles, supports extending above said rows of lower cabinets and forming corner braces for the lower cabinets, upper rows of vertical cabinets carried by said supports and arranged in spaced relation immediately above said lower aisles and being in spaced relation

to each other to define upper aisles immediately above said lower rows of cabinets.

6. A structure of the class described comprising a plurality of rows of lower vertical cabinets arranged in spaced relation to define lower aisles, vertical supports extending above said rows of lower cabinets and forming corner braces for the lower cabinets, upper rows of vertical cabinets carried by said supports and arranged in back to

back relation immediately above said lower aisles and having fronts in spaced relation to each other to define upper aisles immediately above said lower rows of vertical cabinets, and floors carried by said supports and arranged immediately above said lower rows of cabinets to form the floors of said upper aisles. ¹⁵

EDWARD FOOSE.
